PROCESS FOR DEWAXING MINERAL OILS

Sijbren Tijmstra, Berkeley, and Donald S. McKittrick, Oakland, Calif., assignors to Shell Development Company, San Francisco, Calif., a corporation of Delaware

No Drawing. Application June 20, 1936,
Serial No. 86,353

2 Claims. (Cl. 196—18)

This invention relates to a process for separating various waxy substances from mineral oil containing the same. More particularly, it pertains to an improved diluent for decreasing the viscosity of the oil and the solubility of the wax, while improving the solubility of the oil in the liquid phase produced when solid wax is separated from oil, whereby the wax and the oil are separated more readily than has been possible heretofore. This application is a continuation-in-part of our copending application Serial No. 735,626, filed July 17, 1934, which has now matured into Patent No. 2,191,136, dated Feb. 20, 1940.

Mineral oils naturally contain varying amounts of waxy hydrocarbons, often designated as paraffin wax or petrodatum, and hereinafter generally designated as waxes, which at normal or elevated temperatures are dissolved in the liquid hydrocarbons, hereinafter referred to as oil, but which solidify or become extremely viscous at lower temperatures. If these oils are to be used as lubricants at these reduced temperatures the solidified or highly viscous wax causes the oil to resist flow. When the wax content is too low to impede flow, it may, nevertheless, cause cloudiness in the oil. It becomes necessary, therefore, to effect the removal of all or some of the wax.

The first step in such a process is the creation of conditions under which the wax has a minimum solubility in the phase containing the oil. This wax probably contains aliphatic hydrocarbons and/or naphthenic and other hydrocarbons; it belongs to the group of components of petroleum which are the least soluble in selective solvents. The removal of wax may be accomplished by any of several methods.

In accordance with one of these methods, the oil is chilled to a temperature substantially below that at which the wax solidifies and the wax is separated from the liquid oil by mechanical means. As an improvement in such a process, it is common to add a non-selective diluent, such as liquefied, normally gaseous hydrocarbons, light naphthas, etc., to the oil to reduce its viscosity and facilitate the mechanical separation.

In another method, a selective solvent medium is added to the initial oil, and the wax-free components of the initial oil are dissolved therein. This method necessitates the use of a solvent medium which is sufficiently selective to dissolve the oil at a suitable dewaxing temperature without dissolving the wax. The ordinary selective solvents which are employed for exam-

ple in liquid-liquid solvent extraction processes to dissolve certain types of oils which are less paraffinic in nature from those which are more paraffinic in nature are not in general suitable for use as solvent media, because in dewaxing processes the solvent is used to dissolve the desired oil which, in the case of extraction processes, it is desired to recover in the liquid phase insoluble in the solvent.

Certain of such selective solvents may, however, be employed for dewaxing purposes by adding thereto a quantity of a secondary solvent, sometimes referred to as a solubility enhancing solvent. The addition of the secondary solvent improves the miscibility of oil and selective solvent, but in most cases destroys the selectivity of the resulting mixture between wax and oil, so that the resulting mixture of primary selective solvent and solubility enhancing solvent is to a great extent equivalent to a non-selective diluent, and functions only to reduce the viscosity of the chilled oil.

We have discovered that carbon substituted derivatives of furane containing at least one polar substituent, such as —OH, —CHO, —COOH, —COOR, —ROH, —R(OH).R', —RC₂HO, —RCOOH, —RNH₂, —RX (where R stands for an alkyl radical and X stands for halogen and halogen substituted derivatives thereof, which are liquid at dewaxing temperatures in the presence of oil as well as those which become liquid upon the addition of a solubility enhancing agent, are particularly suitable for dewaxing mineral oils. We have, further, found that improved results may be obtained by using these furane derivatives together with one or more solubility enhancing agents. These furane derivatives show a high selectivity between oil and wax, although diluted with solubility enhancing agents. Specific examples of suitable furane derivatives are: furfural, furfuryl amine, furfuryl diamine, furfuryl chloride, methyl furfuryl ether, and n-propyl furfuryl carbinol. Of these, furfural is the most desirable, since it possesses the best solvent characteristics.

These selective solvents may be employed with any suitable enhancing agent which is a good solvent both for oil and for the selective solvent although the solubility enhancing solvent need not be completely miscible with the selective solvent or with the oil in all proportions. Any one or a mixture of many substances may be used as secondary or solubility enhancing solvents, but they should preferably be selected from those solvents which themselves have a low solvent

power for paraffin wax. While a degree of selectivity of the solubility enhancing solvent is not an absolute requirement, it was found that a greater efficiency is generally obtained when a fairly selective solubility enhancing solvent is employed. For example, butyl alcohol usually gives better results than hexane, cyclo-hexane, or benzol.

Numerous specific examples of solubility enhancing solvents are given in the said parent application. It includes, inter alia, aliphatic alcohols, aldehydes, ethers, ketones, all containing between four and twelve carbon atoms such as primary and secondary butyl alcohols, butyl aldehyde, diethyl ketone, hexanone, diethyl ether, diethyl thioether, as well as numerous other compounds, such as carbon bisulfide, aliphatic amines, esters of lower fatty acids and lower aliphatic alcohols containing more than four and less than thirteen carbon atoms, branched chain and cyclic aliphatic hydrocarbons, aromatic hydrocarbons, etc.

While the furane derivatives may be employed with any solubility enhancing solvent, we have found that there exists a class of solubility enhancing agents which is peculiarly adapted for use in connection with these particular selective solvents. This class consists of aliphatic aldehydes containing from four to twelve carbon atoms, and halogenated derivatives of hydrocarbon gases containing from one to five carbon atoms, and particularly the 1,2 dichlor derivatives of aliphatic hydrocarbons having from two to five carbon atoms. The aliphatic chains may be straight or branched chain. Examples of this preferred group of solubility enhancing solvents are: Butyraldehyde, octylaldehyde, chloroform, ethylene dichloride, propylene dichloride, di- and tri-chlorethylenes, butylene dichloride, and 1,1 dichlor butane. Suitable solvent mixtures may, for example, consist of from 10 to 65% of a substituted furane such as furfural and from 35 to 90% of a solubility enhancing solvent.

The method which is the subject of our invention relies primarily on the peculiar properties of the above mixtures of solvents, which were found to create a condition in which there is a large difference between the solubility of the solid or waxy components of the initial oil and the solubility of the liquid or oil components thereof. In one aspect, our method comprises the steps of mixing a waxy oil, such as lubricating oil, fuel oil, etc., which may be either a residual or a distillate oil, with our selective solvent and solubility enhancing solvent, and chilling the resulting mixture to a dewaxing temperature to solidify the wax, which may then be separated from the liquid portion of the system by any mechanical means, such as filtration, cold settling, or centrifuging, depending upon the character of the wax. Our process is, however, particularly suitable for filtration methods. The dewaxing temperature may, for example, be slightly below the melting point of the lowest melting wax which it is desired to remove. The pour point of the dewaxed oil may in certain cases be slightly higher than the dewaxing temperature, but by adjusting the proportions of selective solvent and solubility enhancing solvent, as described below, pour points which are as much as 20° F. below the dewaxing temperature may be obtained.

It is desirable, although not essential, to produce a homogeneous wax-oil-solvent system prior to the precipitation step. To achieve this, the

temperature of the system may initially be raised to somewhat above the dewaxing temperature. We have, moreover, found that excellent filtration rates are obtained by heating the oil-solvent mixture to a temperature within the range from 65° C. to 100° C., or higher, and then cooling it slowly to the dewaxing temperature. When the mixture is initially warmed, it is necessary to cool the oil-solvent mixture, and this may be effected by indirect cooling or auto-refrigeration. Where very low pour points are not essential, our solvent mixtures may often be mixed with the oil at ordinary temperatures of the order of 18° C., thereby obviating the necessity of chilling the oil.

The chilling, when used, is not only for the purpose of merely freezing out the wax, as in the processes now practiced, but also for the purpose of increasing the selectivity of the solvent mixture which may have been added to the oil at a temperature at which it is less selective. This feature distinguishes our process from those in which the wax is caused to separate by mere chilling, and a non-selective solvent or diluent is added to reduce the viscosity of the oil and to expedite the separation of the solidified wax. In this connection it should be noted that the above selective solvents become more selective at lower temperatures.

Under certain conditions the wax which is precipitated according to the procedure outlined above, either with or without chilling during precipitation, may be so soft as to make its separation difficult. It is in these cases advantageous to chill the precipitated wax during or just prior to its final removal to harden it. Subsequently the solvent mixture is removed from the separated liquid by any means, such as distillation.

To be filterable or otherwise separable from the oil-solvent phase, the wax particles must be of suitable form, size and strength and/or hardness. We have found that if in precipitating the wax a very small amount of liquid oil is separated out from the oil with the wax crystals, clusters of crystals are formed and the separation of wax from the solution of oil and solvent is facilitated. The amount of oil necessary for this purpose depends upon the size of the initial wax crystals, which, in turn, depends among other things, upon the nature of the wax and the rate of chilling. In processes in which the crystals are extremely small and the wax content of the initial oil is high, as much as 1.0% of the main body of the oil may be desirable. In other cases, as when the crystals are larger, and/or when less wax is present, lesser amounts of oil may be desirable, and it is frequently practical to permit substantially no oil to be separated out with the wax. Since the separation of an excess quantity of oil reduces the yield of dewaxed oil, it is desirable to control the amount of the oil which is separated with the wax, as described below.

A convenient method of controlling this amount of oil is to regulate the concentration of the solubility enhancing solvent in the solvent mixture. The necessary dilution ratio, i. e., the ratio of the combined solvent mixture to the initial oil, is generally determined by the viscosity of the oil and the solvent mixture and by the selectivity of the solvent mixture at the dewaxing temperature, and is made as low as possible with a view of conserving the solvent. When using the new solvent mixtures of our invention, the dilution ratio may be much lower than the ratio employed with the known solvent mixtures. For example, we have obtained excellent results when

using a dilution ratio of 2:1, and even lower ratios, such as 1:1 may be employed, although we prefer to employ ratios of about 4:1. At very low temperatures, ratios as high as 8:1 may be desirable.

For a given dilution ratio, the greater the concentration of the selective solvent component of the dewaxing mixture, the more complete will be the precipitation of wax, and extremely low pour points may often be obtained. However, since the selective solvent has a relatively low solvent power for the oil, the oil-solvent system will in this case form two liquid phases, in addition to the solid wax phase, and the yield of the dewaxed oil will be extremely low. When an excess of solubility enhancing solvent is employed, the oil-solvent system will exist as a homogeneous liquid phase, and both pour points and yields of dewaxed oil will be increased. Between these concentrations of solubility enhancing solvents, there is a composition of the combined solvent mixture forming a transition point between the liquid-solid and liquid-liquid-solid phase systems. The transition composition will, of course, depend upon several factors, such as the dilution ratio, the dewaxing temperature, the specific solvent employed, and the character of the oil, but may be easily determined empirically for any given situation.

We have found that when the volume concentration of the solubility enhancing solvent in the mixed dewaxing solvent is lower than about 10% below the concentration corresponding to the transition composition, the yields of dewaxed oil are reduced quite out of proportion to the improvement in the pour point. Moreover, we have found that the most efficient dewaxing operations are those which are carried out by employing dewaxing solvent mixtures having compositions near the transition composition, i. e., in which the concentration of the solubility enhancing solvent fall in the range from 10% below to 20% above the transition concentration. Using greater quantities of solubility enhancing agent results in greater yields, but the pour points of the dewaxed oil will often be undesirably high.

Such solvent mixtures as are used in accordance with the present invention may, for example, at temperatures of about 0° F. to -10° F., have complete or substantially complete solubility for oil having specific gravities

d_{45}^{15}

between 0.90 and 0.94 and refractive indices n_{D}^{20} between 1.50 and 1.52, and substantially no solvent power for wax which is solid at the said temperatures, i. e., not more than a few tenths of one per cent of wax will be dissolved at these temperatures; such an oil may, for example, have a viscosity of between 50 and 55 sec. Say. Univ. at 210° F. Mixtures of solvents having this characteristic may, of course, be used also with oils of different refractive indices, specific gravities or viscosities.

The dewaxing process may also be carried out in several steps, the composition of the solvent mixture being regulated, and the process being carried out as described in the U. S. Patent No. 2,126,493, dated August 9, 1938.

The yields of dewaxed oil of a given pour point, and the filtration rates can often be further increased by adding a small amount, generally between 0.2% and 1%, of a pour point reducing substance, such as tetrastearyl glucose, pentaer-

ides, metallic soaps, etc., to the oil preferably prior to chilling. Most of the pour point reducer separates from the oil with the wax, so that it is not normally effective to lower the pour point of the filtrate, but is effective to aid in the formation of filterable wax crystals.

The following examples illustrate the superior results obtainable with improved solvent mixtures. For comparison, the same oil was dewaxed with several of our solvent mixtures, and with acetone-benzol mixtures, the latter mixture being regarded as standard for dewaxing mineral oils.

Example I.—Several samples of a Ventura distillate having a pour point of 95° F. were each diluted with four volumes of various solvent mixtures, heated to produce a homogeneous system, gradually cooled, and filtered at between 0° and 1° C. Diluent compositions and yields are given in percent by volume. The results are shown in the following table:

Exp. No.	Diluent		Yield of dewaxed oil, per- cent	Final pour point of oil, °F.	25
	Selective solvent, percent	Solubility enhancing solvent, percent			
1	Furfural	Ethylene dichloride	91	35	30
		80	89	25	
		75	59	20	
2	Furfural	Octylaldehyde	91	45	35
		75	90	35	
		60	86	30	
		55	73	25	
3	Acetone	Benzol*	94	55	35
		75	92	40	
		50	89	35	
		35	83	30	
		25	53	20

*Contained 10% toluene.

With a dilution ratio of 1 to 4, at 0° C., the following compositions of solvent dewaxing mixtures corresponded to the transition point between one and two liquid phase systems; 24% furfural, 76% ethylene dichloride; 45% furfural, 55% octylaldehyde; 72% acetone, 28% benzol. It will be noted that in each case the yield dropped off sharply when less solubility enhancing solvent was employed than corresponds to the transition point of the solvent in question, with a slight lowering of the pour point, but that with our solvent mixtures we obtain considerably lower pour points at the transition points than with the acetone-benzol mixture. We can, therefore, obtain considerably higher yields for a given pour point, and/or lower pour points for a given yield than with the commonly used acetone-benzol mixtures.

Example II.—The distillate described in Example I was similarly dewaxed with four volumes of a mixture containing 5% furfural and 95% ethylene dichloride, the resulting mixture being heated to 80° C. and filtered at between -19 and -20° C. The dewaxed oil amounted to 82% by volume of the initial oil and had a pour point of -15° F. In a second run, the solvent mixture contained 10% furfural and 90% ethylene dichloride, and 77% of an oil having a pour point of -12.5° F. were obtained. The lowest pour point which could be obtained with acetone-benzol by filtration at -20° C. was 0° F. In this example, the transition composition was that of the first run, i. e., 5% furfural, 95% ethylene dichloride.

Example III.—The distillate described in Ex-

75 thrite tetrastearate, distearyl picene, cracked res-

ample I was similarly dewaxed with four volumes of a mixture containing 25% furfural and 75% octylaldehyde, the resulting mixture being heated to between 97° C. and 100° C. for about an hour, and then filtered at between -19 and -20° C. The dewaxed oil amounted to 89% by volume of the initial oil and had a pour point of -5° F.

These examples are given only for the purpose of illustrating the efficiency of our new solvents, and not by way of limitation. Thus, the oil-solvent ratio may be varied within wide limits. The dewaxing may be carried out either as a continuous or as a batch process. By the term "effective quantity" as used in the claims, we mean a quantity of solvent mixture which will maintain sufficient oil in solution to produce its substantially complete separation from the wax, which is precipitated, and which will produce an oil-solvent mixture of the desired viscosity.

20 We claim as our invention:

1. In the process of manufacturing a low pour

point lubricating oil from wax-bearing mineral oil substantially as described, the step of treating the oil with a liquid solvent mixture to separate solid wax from the oil, said solvent mixture comprising furfural and ethylene dichloride, at temperatures sufficiently low to solidify the wax, in such proportions that the resulting solvent mixture has substantially complete solvent action on the oil and substantially no solvent action on the wax at the dewaxing temperature. 5

2. The process for dewaxing mineral oils which comprises mixing said oil with at least an equal volume of a solvent mixture consisting of between 10 and 65% furfural and between 35 and 90% ethylene dichloride, chilling the resulting mixture to precipitate wax, and removing the precipitated wax from the oil-solvent mixture by mechanical means. 10 15
